UNITED STATES PATENT OFFICE.

HUGH FRANCIS, OF MEMPHIS, TENNESSEE, ASSIGNOR OF ONE-FOURTH TO GEO. E. PETTEY AND ONE-FOURTH TO R. L. DAVIDSON, BOTH OF MEMPHIS, TENNESSEE.

SWING.

1,243,659.

Specification of Letters Patent. Patented Oct. 16, 1917.

Application filed July 1, 1915. Serial No. 37,440.

To all whom it may concern:

Be it known that I, HUGH FRANCIS, a citizen of the United States, residing at Memphis, in the county of Shelby and State 5 of Tennessee, have invented certain new and useful Improvements in Swings, of which the following is a specification.

My invention relates to improvements in porch swings, and particularly to the means 10 for propelling the swing by the foot rest forming a portion of the swing.

The primary object of the invention is the provision of an attachment in connection with the standard type of porch swings by 15 means of which the swing may be propelled by pressure from the foot of the passenger upon the foot rest so that the movement of the swing may be accomplished by the expenditure of comparatively little energy.

20 A further object of the invention is the provision of means for allowing the foot rest to slide under the swing and out of the way when not in use, said means being easy to operate, simple, durable and inexpensive 25 in construction and thoroughly efficient and practical in every particular.

The invention consists in certain novel combinations and arrangement of parts as will be hereinafter set forth and claimed.

30 In the accompanying drawings I have illustrated one complete example of the physical embodiment of my swing constructed according to the best mode I have so far devised for the practical application of the 35 principles of my invention.

Figure 1 is a side elevation of a swing, constructed in accordance with and embodying my invention, with the foot rest in position for use.

40 Fig. 2 is a detail view of one of the guide rods and sliding cuffs mounted thereon.

Fig. 3 is a side elevation of the complete swing as it appears when not in use, and

Fig. 4 is a front elevation thereof.

45 In the preferred embodiment of the invention as illustrated in the drawings, the seat portion of the swing is of usual or suitable construction and of the desired size, embodying the seat A, the back B, and the 50 ends C, while suspending chains or ropes D are utilized to suspend the swing from an

eyebolt secured to an immovable member, as usual.

In equipping a swing with my attachment, I utilize as a foot rest or propeller, 55 the bail or yoke E, preferably of metal, and suspended by a rope or chain F at each end, said rope or chain being attached to a fixed eyebolt. The two curved arms G of the foot rest E are flattened as at H and pivotally 60 connected by means of the pins or studs H' to the cuffs J which are slidably fitted upon the guide rods K, connected to the bottom of the ends C, by the bracket supports L.

It will be readily seen that the swing 65 when hanging is slightly tilted, being somewhat lower at the back than the front, which makes the guide rods K, bolted to it inclined to the rear, and the cuffs which support the ends of the foot rest slide to the 70 rear, as in Fig. 3, when allowed to do so or when the swing is not in use, thus practically putting it under the swing and out of the way, yet ready to be slid forward and in position for use by the slightest pressure of 75 the foot.

In using the device the feet are placed upon the foot rest E, the passenger sitting upon the seat in usual posture, except that instead of the lower limbs from the knee down 80 hanging vertically, they are extended somewhat at an incline to the front of the seat at the knee joint. When pressure is applied to the foot rest by pushing thereon, the center of gravity is changed and the swing naturally oscillates and as the pressure is alternately applied and released, the swing is 85 propelled as will be understood.

It will also be seen that I provide a swing which will be inexpensive of manufacture, 90 simple and durable of construction, which from every point of view will be efficient, practical and durable, and which can be operated with ease and without tiring the user and can be quickly adapted for use 95 when desired.

I claim:

1. The herein described swing, consisting of the suspended seat, the guide rods secured to said seat, the yoke shaped foot rest slidably and adjustably mounted upon said rods, and suspension connections leading from the 100

outer ends of said foot rest and having their upper ends rigidly supported.

2. The herein described swing, consisting of the seat, suspension ropes connected to the 5 said seat, guide rods secured to the underneath portion of said seat, sliding cuffs on said rods, a yoke shaped foot rest adjustably mounted in said cuffs, suspension connection leading from the outer ends of said foot rest

and having their upper ends rigidly supported, and means for securing said cuffs in any desired position.

In testimony whereof I affix my signature in the presence of two witnesses:

HUGH FRANCIS.

Witnesses:

H. C. MCKELLAR,
J. S. HAMPTON.
